UNITED STATES PATENT OFFICE

2,346,984

RATE CONTROL FOR TUNING FORK
OSCILLATORSMilton S. Mead, Jr., Hempstead, N. Y., assignor
to General Electric Company, a corporation of
New York

Application August 25, 1942, Serial No. 456,001

7 Claims. (Cl. 250—36)

My invention relates to oscillation generators, and more particularly to oscillation generators employing an electron discharge control device and including a frequency determining system of the mechanically vibratory type. It is an object of my invention to provide a control for such an oscillator which allows a wide range of adjustment of the rate of mechanical vibration of the frequency determining system.

In applications where it is necessary to maintain the output frequency of an oscillator substantially constant over long periods of time, as in clock supervisory systems, for example, oscillators employing a mechanically vibratory element, for example a tuning fork, have been found particularly suitable. Such oscillators usually include drive and pick-up coils associated with the tuning fork, which coils are coupled respectively to the output and input circuits of an electron discharge amplifier and are so arranged that vibration of the element controls the amplifier to produce sustained oscillations in the output circuit thereof.

It is an object of my invention to provide in an oscillation generator of the above described type means for controlling the frequency of vibration of the vibrating element which, while allowing a wide range of adjustment of the rate of vibration, maintains a constant amplitude of vibration of the vibrating element and consequently constant output voltage from the electron discharge amplifier.

A further object of my invention is to provide means for varying the frequency of vibration of a vibratory element by shifting the phase angle between the current in the driving coil and the vibrations of the element in such a manner that the change in frequency varies linearly with the position of a manual control member.

Another object of my invention is to provide a tuning fork oscillator having an adjustable rate of vibration which can be easily produced in large quantities and which includes means for readily adjusting the range of rate control for such production units.

The features of my invention which I believe to be novel are set forth with particularity in the appended claims. My invention itself, however, together with further objects and advantages thereof, may best be understood by reference to the following description taken in connection with the accompanying drawing, in which Fig. 1 illustrates one embodiment of my invention; Fig. 2 shows vectorially certain voltage relationships pertaining thereto; Fig. 3 shows an

example of the scale possible in the rate control device; and Figs. 4 and 5 illustrate schematically modifications of my improved rate control.

Referring to Fig. 1 of the drawing, I have shown my improved oscillation generator as comprising an amplifier, including an electron discharge device 1, which is controlled by a vibratory element 2 to generate electrical oscillations having a frequency determined by the frequency of vibration of the element 2. The vibratory element 2 is shown as a tuning fork, although it will be understood that other forms of mechanical vibratory elements may be employed without modification of the circuit illustrated. The output of the device 1 is impressed upon the input circuit of a second amplifying device 3 which in turn has its output circuit coupled to a utilization circuit (not shown) by the leads indicated at 4.

Electron discharge device 1 is shown as being of the single diode pentode type and includes an anode 5, a cathode 6, control electrodes 7, 8 and 9 and a diode electrode 10, control electrode 9 being directly connected to the cathode 6 and functioning as the usual suppresser grid to prevent secondary electron emission within the discharge device. The electron discharge device 3 is similar in all respects to device 1, with the exception that the single diode electrode is omitted.

The input circuit to the amplifier 1 includes a secondary 11 of a coupling transformer 12 having its primary 13 connected to a pick-up coil 14 wound on the field structure of the tuning fork 2. For a purpose to be explained more fully later, the input circuit is connected across a phase shifting circuit, comprising resistance 15 and capacitor 16, the voltage across the capacitor 16 being impressed between the control electrode 7 and the cathode 6 of the discharge device 1 through an alternating current by-pass condenser 17.

The output circuit of the amplifier 1 includes the primary winding 18 of a coupling transformer having its secondary winding 19 connected through a rate control network 20, the nature and function of which will be described in detail later, to excite a fork drive coil 21. The winding 18 is connected between the anode 5 and cathode 6 of the device 1 in series with a source of high voltage direct current potential 22 and a resistance 23. A condenser 24 is connected in shunt with the winding 18 and functions to tune the inductance of the winding to form an oscillatory circuit 25 having a resonant

frequency equal to the normal operating frequency which the apparatus is designed to produce.

The potential developed across the terminal of the oscillatory circuit 25 is impressed upon a resistance 26 connected to the oscillatory circuit by a pair of alternating current by-pass condensers 27 and 28 included in the input circuit of device 3. Resistance 26 is connected between the control electrode and cathode of the discharge device 3 through a by-pass condenser 29. A resistance 30, connected at one end to the negative side of the voltage source 22, serves to bias the control electrode of the device 3 negative with respect to the cathode thereof.

The output circuit of the electron discharge device 3 includes the leads 4 connected respectively to the anode and cathode of the device 3 and shunted by the tuning capacitor 31. A source of anode voltage comprising the potential drop across a pair of series connected resistances 32 and 33 is also included in the output circuit between the cathode of the device 3 and one terminal of the condenser 31.

A positive potential is supplied to the screen electrode of device 3 through the voltage dropping resistor 33. This resistor serves to maintain the screen electrode at a positive potential slightly lower than the positive potential of the anode of device 3. In similar manner a biasing potential is impressed on screen electrode 8 of device 1 through the circuit lead which includes a voltage dropping resistor 34.

The vibratory frequency determining unit for controlling the amplifier system described above includes the tuning fork 2 and a field structure comprising the core members 35, 36, upon which the drive and pick-up coils respectively are wound, and the permanent magnet member 37. Since this structure forms no part of my present invention, it will not be described in detail; instead, a description of this structure may be found in my United States Letters Patent No. 2,147,492, granted February 14, 1939, and assigned to the same assignee as the present invention. The intensity of the unidirectional flux flowing between members 35 and 36, and in turn the negative compliance or stiffness of the tines of fork 2 may be adjusted by means of winding 38 on member 37 which is connected in series with the battery 39 and the switch 40.

As has been previously noted herein, my present invention is primarily concerned with the problem of providing means by which the rate of mechanical vibration of the tines of fork 2 may be varied over a wide range. For this purpose the rate control network 20 is provided across the secondary winding 19 supplying the fork drive coil 21. This network comprises capacitor 41 and resistance 42 connected in series across winding 19 and having a common point 43 to which is attached one terminal of the drive coil 21. A fixed resistance 44 connected in shunt with the above mentioned series circuit is provided with a variable point 45 to which the other terminal of drive coil 21 is connected through secondary winding 46 of transformer 47, the primary winding 48 of transformer 47 being connected in series with pick-up coil 14 and the primary winding 13 of transformer 12.

Operation of the above described oscillation generator may be initiated by impressing a current impulse on the drive coil 21. Such an impulse changes the path of the flux, flowing between the core members 35 and 36 through the

tines of fork 2 by attracting or repelling these tines in accordance with the polarity and magnitude of said current impulse. Such movement of the tines of fork 2 alters the magnetic flux linking pick-up coil 14, generating in the pick-up coil an electromotive force which is a function of the current flowing in drive coil 21. This electromotive force is impressed on the control electrode 7 of amplifier 1 through the coupling transformer 12 and phase shifting network 15, 16, where a phase shift of 90° is obtained, and causes an impulse of energy to flow in the output circuit of device 1. A portion of this impulse of energy developed in the output circuit is delivered through the secondary winding 19 to the rate control circuit 20. When the variable contact 45 is adjusted to the mid point on the resistor 44, rate control network 20 produces a phase shift equal and opposite to that obtained in the phase shifting network 15 and 16. Under such conditions a current impulse flows in drive coil 21 in a direction opposite to the current flow of the initial current impulse. This produces an opposite movement of the tines of fork 2 causing a second voltage impulse to be generated in pick-up coil 14 having a sign opposite to that caused by the first movement of the tines. This second impulse of voltage exerts a controlling effect on the device 1 such that the instantaneous current flowing in the output circuit thereof is reversed in direction for the duration of the impulse. The interaction of fork vibration and amplifier ultimately reaches a condition of equilibrium in which the fork is vibrated at a substantially constant frequency determined by the amplitude of the alternating current in the drive coil 21, the intensity of the unidirectional flux between members 35 and 36 and the natural period of vibration of the fork.

By adjustment of the position of variable contact 45, the phase between the voltage applied across the terminals of drive coil 21 and the vibrations of the fork may be altered so that the driving force exerted by the drive coil either leads or lags the fork vibrations. When the driving current is in phase with the vibrations of the fork, and hence with the pick-up voltage, the fork operates at its natural frequency. If the driving current is made to lag behind the vibrations of the fork, it reduces this frequency to a value below the natural frequency. On the other hand, if the driving current leads the vibrations of the fork, the rate of vibration is increased.

The manner in which my control acts to increase or decrease the rate of vibration of the element 2 may be explained by reference to Fig. 2. In Fig. 2 if the vector E represents the voltage across the terminals of the winding 19, voltages across resistance 42 and capacitor 41 are shown respectively by vectors E_R and E_C. The current flowing through the series circuit of resistor 42 and capacitor 41 is shown by the vector I. It is, of course, apparent that the voltage E represents likewise the voltage existing across resistance 44. The vector E_D, therefore, represents the voltage applied across the drive coil 21 when the variable point 45 is adjusted to the mid position of resistor 44. Under such conditions, the circuit constants are adjusted so that the driving force produced by the current flowing in drive coil 21 is in phase with the vibrations of the fork. When the variable contact 45 is moved to some other position, such as 45', the voltage applied across the terminals 43, 45 of the drive coil circuit is represented by the vector E'D. Under these con-

ditions the driving force lags the vibrations of the fork and reduces the output frequency of the system. The increased driving current secured when the control is off center position is automatically the amount required to furnish the increased driving force necessary to cause the fork to vibrate with the same amplitude at the new phase angle, which the fork must assume to match the phase shift through the amplifier. As a result of this constant amplitude of vibration of the fork, the magnitude of the voltage generated in the pick-up coil 14 remains constant, resulting in a constant output voltage for the amplifiers 1 and 3. The out-of-phase component of the voltage $E'D$ is effective to reduce or increase the frequency of the voltage appearing in the pick-up coil 14 with resultant variation in the frequency of a voltage across the terminals 44. Moreover, the vector diagram of Fig. 2 shows that the magnitude of this out-of-phase component of the voltage of $E'D$ varies linearly with the adjustment of the contact 45 from the mid point of resistance 44.

Fig. 3 shows an example of the scale which may be used for the rate control when a well known type of potentiometer is used for the variable resistance 44. The actual value of increase or decrease in frequency is a function of the decrement of fork 2. If the fork has a very low decrement, it can vibrate with a large phase angle between the driving force and the fork velocity without experiencing but a slight change in frequency.

In order to neutralize the effect of voltages generated in the drive and pick-up coils due to the inductive coupling between these two coils, the coils are both loosely coupled and transformer 47 is provided, with its windings 46 and 48 connected respectively in the drive and pick-up circuits, to introduce in either of the two circuits a potential which is opposite in phase to the potential generated by the coupling of the coil windings and equal in magnitude to the voltage produced by such coupling.

Also, in order to maintain as nearly constant as possible the magnitude of the output current of the amplifier 1, a circuit is provided for supplying a biasing potential to control electrode 7 of device 1 which varies in accordance with the intensity of the output current flowing between the anode 5 and the cathode 6. This automatic biasing circuit, comprising the diode formed by the element 10 and the cathode 6, coupling capacitor 49 and resistances 50 and 51, functions to maintain substantially constant the anode current of device 1 by utilizing the unidirectional current flowing between element 10 and cathode 6, resulting from the alternating potential impressed thereacross through capacitor 49, to develop a unidirectional potential across resistor 50. This unidirectional potential is impressed on control electrode 7 through resistance 51 and winding 11 of transformer 12 and varies the biasing potential impressed on the control electrode 7 with, and in proportion to, the magnitude of the current flowing in the anode circuit of the amplifier.

In order to provide a constant potential for the screen electrode 8 of device 1, an electric discharge device 52 is connected between the electrode 8 and the cathode 6. Since the screen electrode 8 is connected to the source of potential 22 through resistance 34, the device 52, which may comprise an ordinary glow discharge tube having a pair of spaced electrodes positioned within a container filled with an ionizable medium, such

as neon, acts in a well known manner to vary the current flow in direct proportion with variations of the potential source 22, thus maintaining the potential of the grid 8 with respect to the cathode 6 at a constant value. In this manner the magnitude of the current supplied to the drive coil 21 is maintained substantially constant. Switch 53 is provided in order to supply a high voltage impulse for starting tube 52.

In the rate control for a tuning fork oscillator illustrated in Fig. 1, a wide range of adjustment may be secured by varying the position of contact 45 between the extreme limits of resistor 44, a phase shift of $\pm 45^\circ$ in operation being secured with constant fork amplitude.

In Fig. 4 is shown one modification of the control illustrated in Fig. 1. In this figure, parts corresponding to Fig. 1 are identified by corresponding reference characters. In this modification fixed resistors 54 and 55, of equal ohmic value, are connected in series with resistor 44, decreasing the range of rate variation.

In the modification illustrated in Fig. 5, I have shown how my rate control may be connected between the pick-up coil and the input to the fork amplifier when operating conditions make such a change desirable.

It will thus be seen that my improved oscillation generator provides means whereby a wide range of adjustment of the rate of vibration of a mechanical vibratory element may be secured while the output voltage from the vibration amplifier is held constant for all settings of the rate control. Moreover, my control is characterized by the linear relationship between the change in frequency and the change in the setting of a potentiometer.

While I have shown particular embodiments of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. In combination, a vibratory element, means associated therewith for generating a voltage having an intensity determined by the amplitude of vibration of said element and a frequency determined by the frequency of vibration of said element, an output circuit connected to said voltage generating means, means including a drive coil coupled to said output circuit for supplying a driving force to said element, and means for varying the phase between said driving force and said element, said phase varying means comprising a resistance and capacitor connected in series across said output circuit, a second resistance connected in shunt therewith, and means for connecting said drive coil between the common point of said resistance and capacitor and a variable point on said second resistance.

2. In combination, an oscillation generator comprising a vibratory element, an electron discharge device having an anode, a cathode, and a control electrode, input and output circuits connected to said device, means including a drive coil coupled to said output circuit for supplying a driving force to vibrate said element, means including a pick-up coil for controlling the frequency of current in said output circuit in accordance with the frequency of vibration of said element, and means for varying the frequency of vibration of said element, said last-named means

comprising a phase-shifting circuit connected across said output circuit, and means for adjustably connecting said drive coil across said phase-shifting circuit, whereby the phase angle between said driving force and said element is varied.

3. In combination, an oscillation generator comprising a vibratory element, an electron discharge device having an anode, a cathode, and a control electrode, input and output circuits connected to said device, means including a drive coil coupled to said output circuit for supplying a driving force to vibrate said element, means including a pick-up coil for controlling the frequency of current in said output circuit in accordance with the frequency of vibration of said element, and means for varying the frequency of vibration of said element, said last-named means comprising a capacitor and a first resistance connected in series across said output circuit, said capacitor and first resistance having a common point, a second resistance connected in shunt to said output circuit, and means for connecting said drive coil between said common point and a variable point on said second resistance, whereby the phase angle between said driving force and said element may be varied.

4. In combination, a vibratory element, means associated therewith for generating a voltage having an intensity determined by the amplitude of vibration of said element and a frequency determined by the frequency of said vibration, and means for varying the frequency of said vibration while maintaining the amplitude of said vibration constant, said means comprising an output circuit connected to said voltage generating means, phase-shifting means connected across said output circuit, and means including a driving coil connected to said phase-shifting means for supplying a driving force to said element, the phase angle between said force and said vibration being adjustable.

5. In combination, a vibratory element, means associated therewith for generating a voltage having an intensity determined by the amplitude of vibration of said element and a frequency determined by the frequency of said vibration, an amplifier having input and output circuits, means including a phase-shifting circuit connecting said voltage generating means to said input circuit, and means for varying the frequency of said vi-

bration while maintaining the amplitude of such vibration constant, said means comprising phase-shifting means connected across said output circuit, and means including a driving coil connected to said phase-shifting means for supplying a driving force to said element, the phase angle between said force and said vibration being adjustable.

6. In combination, an oscillation generator 10 comprising a vibratory element, an electron discharge device input and output circuits connected to said device, means including a drive coil coupled to said output circuit for supplying a driving force to vibrate said element, means includ-

15 ing a pick-up coil for controlling the frequency of current in said output circuit in accordance with the frequency of vibration of said element, and means for varying the frequency of vibration of said element, said last-named means comprising

20 a phase-shifting circuit connected between said pick-up coil and said input circuit, a phase shifting circuit connected across said output circuit, and means for adjustably connecting said drive coil across said last phase-shifting circuit, 25 whereby the phase angle between said driving force and said element may be varied.

7. In combination, an oscillation generator comprising a vibratory element, an electron discharge device, input and output circuits connected

30 to said device, means including a drive coil coupled to said output circuit for supplying a driving force to vibrate said element, means including a pick-up coil for controlling the frequency of current in said output circuit in accordance with

35 the frequency of vibration of said element, and means for varying the frequency of vibration of said element, said last-named means comprising a phase-shifting circuit connected between said

40 pick-up coil and said input circuit, a capacitor and a first resistance connected in series across said output circuit, said capacitor and first resistance having a common point, a second resistance connected in shunt to said output circuit, and means for connecting said drive coil between said common point and a variable point 45 on said second resistance, whereby the phase angle between said driving force and said element may be varied.
